UNITED STATES PATENT OFFICE.

EDWIN M. WHITNEY, OF LANSDALE, PENNSYLVANIA, AND JOHN B. HABERLE, OF SOUTH BEND, INDIANA, ASSIGNORS TO PERKINS GLUE COMPANY, A CORPORATION OF PENNSYLVANIA.

GLUE-SPREADER.

1,202,337.

Specification of Letters Patent. Patented Oct. 24, 1916.

Application filed May 6, 1914. Serial No. 836,800.

To all whom it may concern:

Be it known that we, EDWIN M. WHITNEY and JOHN B. HABERLE, citizens of the United States, the former a resident of 5 Lansdale, county of Montgomery, State of Pennsylvania, and the latter a resident of South Bend, county of St. Joseph, State of Indiana, have invented certain new and useful Improvements in Glue-Spreaders, of 10 which the following is a specification.

The invention relates to improvements in glue spreaders and more particularly to spreaders adapted to apply a specially viscous glue such as described in Letters Patent 15 No. 1,020,656 and Reissue Letters Patent No. 13,436.

Such spreaders are particularly adapted to spreading glue on wood veneers and in such work with the form of scrapers heretofore used in this class of spreaders it has been found that sawdust, chips and other foreign matter is prone to collect between the scrapers and the glue applying rolls, thus preventing not only an even spread, but 25 in many cases so completely obstructing the flow of the glue as to cause dry streaks, which seriously affect the quality of the work and make it necessary that the machines be frequently stopped, in order that 30 the space between the scrapers and glue applying rolls be periodically cleaned out.

The main object of this invention is to provide apparatus in which these disadvantages do not occur and in which the space between 35 the scraper and glue applying rolls is automatically cleaned of all such foreign matter.

Further objects of the invention are to provide improved means for adjusting the scraper to and from the glue applying rolls, 40 and to provide a machine with both upper and lower glue applying rolls, in which the pressure exerted between the rolls upon the material being glued may be more satisfactorily adjusted and in which fingers are provided for stripping the material from the 45 rolls, which may easily and conveniently be adjusted toward the glue applying rolls.

Further objects, features and advantages will more clearly appear from the detailed 50 description given below, taken in connection with the accompanying drawings which form a part of this specification, and in which—

Figure 1 is a side elevation of a machine embodying the invention in its preferred 55 form; Fig. 2 is a front elevation of the same, and Fig. 3 is a vertical section taken on the line 3—3 of Fig. 2.

Referring to the drawings: 1 represents suitable framework having journaled therein 60 at 2 a glue applying roll 4. The roll dips in a glue trough 5. Hinged at 6 at the front of the glue trough 5 is an upright front piece 7, having integral therewith a horizontal table 8 on which the veneers or materials to be glued are laid as they are fed into the spreader. Secured to the table 8 as by screw bolts 9 are end pieces 10 in which is journaled a roller 11 co-operating as a scraper for the glue applying roll 4. 65 Springs 12 are provided, one at each end of the machine, each spring having one end abutting against the frame of the machine and the other end abutting against the under side of an extension 13 of the table 8, 75 which springs tend to oscillate the table upward about its pivot at 6, carrying with it the roller 11 thus tending to move the roller 11 away from the glue roll 4. The roller 11 is drawn toward the roll 4 against the 80 tension of the springs 12 by means of hand nuts 14 threaded on the ends of links 15 having their opposite ends pivoted in the framework at 16. (Fig. 1.) The links 15 at their outer ends engage lateral slots in the 85 extensions 13 against which the nuts 14 bear. Consequently, by screwing up on the hand nuts 14 the table 8 is pulled forward and the roller 11 downward against the action of the springs 12 so that the roller may 90 be adjusted toward and from the glue roll 4 to vary the thickness of the layer of glue on the latter, the springs acting to force the roller 11 away from the roll 4 upon a release of the nuts 14.

In order to periodically give the roller scraper 11 a rotary movement, a ratchet wheel 16 is secured to the shaft thereof at one end, which ratchet is operated by a spring pressed pawl 17 pivoted on an arm 18, which arm 18 is journaled on the shaft of the roller 11. The arm 18 is engaged by a cam 19 (Fig. 1) on the shaft of the glue roll 4, which oscillates the arm 18 causing the pawl 17 and ratchet 16 to periodically 100 move the roller 11 with respect to the glue 105

roll 4, that is, give it a rotary movement, so that all dirt, chips or other foreign matter which may have collected in the narrow space between the roller 11 and roll 4 will 5 be carried through between the rolls and not allowed to collect sufficiently to cause any unevenness in the layer of glue left on the roll 4 to be applied to veneers.

The machine is also provided with an upper glue applying roll 20 extending into the bottom of an upper glue trough 21 from which it derives its glue, the roll 20 being journaled in the ends of arms 22 at 23, the arms 22 being pivoted in the main frame 15 of the machine at 24 and having rearwardly extending portions 25, engaged by links 26 having their lower ends engaging arms 27 rigidly secured to a square shaft 28 journaled in the main frame at 29. The shaft 20 28 also has a third bearing at 30 in a depending frame piece 31. Also rigidly secured to the shaft 28 is an upright arm 32 engaged by a screw 33 working in the main frame and operated by a hand wheel 34. By 25 turning the hand wheel 34 so as to advance the screw 33 inwardly, the shaft is rotated, forcing arms 27 downwardly which, by means of the links 26 pull the arms 25 downwardly so as to raise the upper roll 20 and 30 so adjust its position with respect to the lower roll 4. The upper roll 20 is pulled downwardly by means of weights 35 adjustable on the ends of horizontal arms 36 pivoted in the main frame at 37, the arms 36 being engaged by upright rods 38 passing through extensions 39 integral with the arms 22 and engaged by thumb nuts 40 on their upper ends, so that by turning the thumb nuts the rods 38 may be pulled up or lowered 40 in order to adjust the position of the weight carrying arms 36.

The upper glue trough 21 is pivoted at 41 to the integral extension of the arm 22 and has journaled in its ends at the bottom 45 of the trough a roller scraper 42 coöperating with the upper glue roll 20. Links 43 pivoted to the inner ends of the arms 22 are screw-threaded on their outer ends and engaged by hand nuts 44, which engage slotted 50 extensions 45 attached to the front of the upper glue trough and through which the links 43 pass. Rigid on the links 43 are nuts 46 and springs 47 surrounding the links 43 have one end abutting against the nuts 46 55 and their opposite ends abutting against the extension 45. Upon screwing up upon the nuts 44 the lower part of the glue trough 21 is moved inwardly against the action of the springs 47 carrying with it the roller scraper 42 so that the same may be adjusted toward 60 and from the roll 20, the roller 42 being moved away from the roll 20 by the springs 47 upon the loosening up of the nuts 44.

In order to give the roller scraper 42 a 65 periodic rotary movement so as to clear any

foreign matter from between it and the roll 20, a ratchet 48 is secured to the shaft of the roller 42 outside the upper glue trough, which ratchet is operated by a pawl 49 pivoted on an arm 50 which arm is pivoted 70 to the upright extension of the arm 22 at 51 (Fig. 1). The rear end of the arm 50 is oscillated up and down by being connected with the oscillating arm 18 by means of a link 52. A weight 53 holds the arm 18 down 75 against the cam 19.

In order to strip the wood veneer or other material being glued, from the glue rolls 4 and 20, these rolls are provided with circumferential grooves 54 (Fig. 2) and pointed 80 fingers 55 engage the grooves in the lower glue roll for this purpose, which fingers 55 are twisted and bent downward at their rear ends at 56 and adjustably secured to the lower glue trough by screw bolts 57 passing 85 through slots in the downwardly bent portion of the fingers. Likewise pointed fingers 58 engage the circumferential grooves in the upper roll 20 which fingers are supported by the shaft 59 (Fig. 2) to which the arms 22 90 are secured. The fingers 58 are made adjustable by securing them to the shaft 59 by means of split collars, each having two parts 60 and 61 secured together about the shaft 59 on one side, by means of a screw-bolt 62 95 and on the other side by means of a thumb screw 63, so that by loosening the thumb screws 63 the fingers 58 may be adjusted toward the glue applying roll and then the thumb screws 63 tightened to maintain the 100 fingers in adjusted position.

To drive the machine, power is applied to the shaft 64 which carries a pinion meshing with a pinion 65 on the shaft of the lower glue roll 4 so as to drive the latter. At its 105 other end the shaft 64 carries a sprocket wheel over which passes a sprocket chain 66. The chain 66 passes over an idler 67 and thence over a sprocket wheel 68 loosely mounted on the shaft 59. Another sprocket 110 wheel rigid with the sprocket wheel 67 drives a sprocket chain 69 which chain drives a sprocket wheel 70 rigid with the shaft of the upper glue roll 20 so that the upper glue roll is driven from the power 115 shaft 64 and movement of the upper and lower glue rolls 20 and 4 toward and away from one another does not tighten or loosen the sprocket chains.

From the above it will be clear that the 120 invention comprehends a glue spreader having a roller scraper coöperating with one or both of the glue applying rolls, whereby dirt, chips, sawdust and other foreign matter will be automatically freed from between the scraper and the glue applying roll. By the term "foreign matter" is meant any and all matter which tends to clog up the space between the scraper and glue applying roll, so as to cause an interference 130

in the spread or a failure of spread in streaks, and such foreign matter may include even hardened or jellified portions of the glue itself, which would clog or hinder the flow of the glue through the space between the scraper roll and the glue applying roll. It will be seen that by giving the scrapers 11 and 42 a rotary movement with respect to the glue applying rolls, that any foreign matter which may collect in the glue troughs and tend to enter between the scraper rolls and glue applying rolls will be carried through between them and not allowed to clog sufficiently to cause streaks or other disadvantages in the spread.

The means for periodically oscillating the roller scrapers by means of pawls and ratchets forms an efficient positive means for periodically moving the scraper rollers to accomplish the above mentioned purpose.

The special adjustments mentioned have also important advantages, as will be clear to those skilled in the art, upon reading the above description.

Although the means have been described in connection with the one particular machine and in great detail with respect thereto, yet it will be clearly understood that many changes and modifications may well be made in the apparatus without departing from the spirit of the invention and its scope and in its broader aspects, as set forth in the appended claims.

Having fully and clearly described the improvements, what is claimed and desired to be secured by Letters Patent is:—

1. A glue spreader having a glue roll for applying the glue to the material to be glued and an intermittently operated roller scraper coöperating therewith to regulate the amount of glue applied.

2. A glue spreader having a glue roll for applying glue to the material to be glued and an intermittently movable scraper co-operating therewith whereby foreign matter will be automatically freed from between the scraper and glue applying roll.

3. A glue spreader having a glue roll for applying glue to the material to be glued, a scraper coöperating therewith and means intermittently moving the scraper relatively to the roll whereby foreign matter will be automatically freed from between the scraper and the glue applying roll.

4. A glue spreader having a glue roll for applying glue to the material to be glued, a scraper coöperating therewith and means for automatically moving said scraper intermittently, to permit foreign matter to be automatically freed from between the scraper and the glue applying roll.

5. A glue spreader having a glue roll for applying glue to the material to be glued, a scraper coöperating therewith and means for periodically giving said scraper a ro-

tary movement, whereby foreign matter will be automatically freed from between the scraper and the glue applying roll.

6. A glue spreader having a glue roll for applying glue to the material to be glued, a roller scraper therefor and means for automatically periodically giving said scraper a rotary movement, whereby foreign matter will be automatically freed from between the scraper and the glue applying roll.

7. A glue spreader having a glue roll for applying glue to the material to be glued, a scraper therefor and means for automatically periodically moving said scraper without affecting the spread of the glue, whereby foreign matter will be automatically freed from between the scraper and the glue applying roll.

8. A glue spreader having a glue roll for applying glue to the material to be glued and a roller scraper coöperating therewith to regulate the amount of glue applied, means intermittently moving the scraper relatively to the glue roll and means for adjusting the scraper to and from the glue applying roll.

9. A glue spreader having a glue roll for applying glue to the material to be glued, a scraper coöperating therewith and means for automatically periodically moving said scraper, whereby foreign matter will be automatically freed from between the scraper and the glue applying roll, and means for adjusting the scraper to and from the glue applying roll.

10. A glue spreader having a glue roll for applying glue to the material to be glued, a roller scraper therefor and means for automatically periodically giving said scraper a rotary movement, whereby foreign matter will be automatically freed from between the scraper and the glue applying roll, and means for adjusting the scraper to and from the glue applying roll.

11. A glue spreader having upper and lower glue applying rolls, a roller scraper for each glue applying roll, and means for automatically periodically giving each scraper a rotary movement, whereby foreign matter will be automatically freed from between the scraper and the glue applying roll.

12. A glue spreader having a glue roll for applying glue to the material to be glued, a roller scraper therefor and a cam mechanism automatically periodically moving the scraper, whereby foreign matter will be automatically freed from between the scraper and the glue applying roll.

13. A glue spreader having upper and lower glue troughs, upper and lower glue applying rolls receiving glue from said troughs respectively, a roller scraper for each glue applying roll, each scraper be-

ing automatically periodically given a rotary movement, whereby foreign matter will be automatically freed from between the scrapers and the glue applying rolls.

5 14. A glue spreader having upper and lower glue troughs, upper and lower glue applying rolls receiving glue from said troughs respectively, a roller scraper for each glue applying roll, each scraper being 10 automatically intermittently given a rotary movement, whereby foreign matter will be automatically freed from between the scraper and the glue applying roll, and means for adjusting each scraper to and from its glue 15 applying roll.

15. In a spreading machine the combination of a roll for applying the material to be spread, and a scraper for said roll automatically given an intermittent rotary movement, 20 whereby foreign matter will be automatically freed from between the scraper and the roll.

16. In a spreading machine the combination of a roll for applying the material to be spread, a rotating scraper for said roll and means for automatically giving said scraper an intermittent rotary movement, whereby 25 foreign matter will be automatically freed from between the scraper and the roll.

30 17. In a spreading machine the combination of a roll for applying the material to be spread, a roller scraper for said roll and a pawl and ratchet mechanism for automatically periodically giving said scraper a rotary movement, whereby foreign matter will be automatically freed from between the 35 scraper and the roll.

18. A glue spreader having a glue applying roll, a scraper therefor adjustable toward 40 and from the roll, a spring or springs tending to force the scraper away from the roll,

means for intermittently moving the scraper to free foreign matter from between the roll and scraper, and a means for forcing the scraper toward the roll in opposition to the 45 spring or springs to adjust the position of the scraper with respect to the roll.

19. A glue spreader having a glue applying roll, a scraper therefor adjustable toward and from the roll, means intermittently 50 rotating the scraper, a spring or springs tending to force the scraper away from the roll and a hand nut or nuts for forcing the scraper toward the roll in opposition to the spring or springs to adjust the position of 55 the scraper with respect to the roll.

20. A glue spreader having upper and lower glue applying rolls, a roller scraper for each glue applying roll, a pawl and ratchet mechanism for periodically giving 60 each scraper a rotary movement, whereby foreign matter will be automatically freed from between the scraper and the glue applying roll, springs tending to force the scrapers away from their respective rolls and 65 hand nuts for forcing the scrapers toward their respective rolls in opposition to the springs to adjust the position of the scrapers with respect to their respective rolls.

In testimony whereof, we have signed our 70 names to this specification in the presence of two subscribing witnesses.
